United States Patent Office

Des. 230,141

Patented Jan. 29, 1974

230,141

SERVICE CART

Matthew N. Miller, Woodland Hills, Calif., assignor to
Fairchild Industries, Inc., Germantown, Md.

Filed Mar. 8, 1973, Ser. No. 339,135

Term of patent 14 years

Int. Cl. D12—02

U.S. Cl. D12—29

Fig. 1

Fig. 2

Fig. 3

Fig. 4

FIG. 1 is a perspective view of a service cart showing my new design;

FIG. 2 is a top plan view thereof;

FIG. 3 is a side elevational view, the opposite side being substantially a mirror image thereof; and

FIG. 4 is an end elevational view, the opposite end being substantially a mirror image thereof.

I claim:

The ornamental design for a service cart, substantially as shown and described.
